UNITED STATES PATENT OFFICE.

JOSEF PEJCHAR, OF BROOKLYN, NEW YORK.

LOCKING DEVICE FOR BROOCHES AND THE LIKE.

Application filed January 26, 1923. Serial No. 615,048.

To all whom it may concern:

Be it known that I, JOSEF PEJCHAR, a citizen of the United States, and resident of the borough of Brooklyn, county of Kings, 5 city and State of New York, have invented certain new and useful Improvements in Locking Devices for Brooches and the like, of which the following is a specification.

My present invention relates to locking 10 devices for brooches, pins and similar articles, and it has for its object to provide a device of this character which is simple in construction and operation, and which will enable the article of which it forms part, 15 to be worn without danger of its getting lost owing to the accidental opening of its securing means.

Without desiring to restrict myself to the 20 exact details shown, I have illustrated in the accompanying drawings two satisfactory forms of my invention. In these drawings, Fig. 1 is a perspective view of a brooch or bar pin provided with my new locking device; Figs. 2 and 3 are transverse sections 25 taken on line 2—2 and 3—3 respectively of Fig. 4; Fig. 2 showing the locking device in the open position and Fig. 3 showing it in the closed or locking position; Fig. 4 is a side view of the left-hand end of Fig. 1; 30 and Fig. 5 is a view similar to Fig. 4, but illustrating a slightly modified form of the locking device.

10 represents a brooch or bar pin which at its right-hand end (Fig. 1) is formed with 35 the usual hinge 11 supporting pivotally one end of the securing pin 12 the other, pointed end of which is adapted to be held and locked in position by my improved locking device. This locking device comprises 40 a holder or keeper 13 rigidly secured to the brooch 10 and formed of two parallel, spaced walls 14, 15 connected at one end by a short wall 16 transverse to the planes of the two parallel walls. The keeper 13 is 45 provided with a slot extending inwardly from the wall 16 as shown at 17, and then upwardly in the direction toward the upper edge of the keeper 13, this upper slot portion 18 serving to receive the free end of the 50 securing pin 12 which has been introduced through the open end of the slot 17. The two slot portions are so formed as to have at their meeting point an inwardly-projecting nose 19. 55 Between the parallel walls 14, 15 is arranged movably a locking member or plate

20 hinged to said walls by a hinge pin 21 and formed with a slot 22 which also serves to receive the securing pin 12 when the plate 20 is swung into locking position. The slot 60 22 also is formed with a projecting nose 23 which cooperates with the projection 19 in a manner which will be described below. The slot 22 divides the plate 20 into two parts the outer one of which, 24 forms a lip 65 which serves to guide the locking plate 20 in its swinging movement, and which also has another purpose which will be described further on. At its upper end, that is, at its portion farthest away from the pivot 21, the 70 locking member 20 is provided with a rounded projection 25 which forms a handle for the convenient manipulation of the locking member.

The operation of my locking device is as 75 follows: Before the brooch or other article is secured in place, the locking member or plate 20 is brought to the open position, Fig. 2. The article is then placed in its position on the garment by passing the securing 80 pin 12 through the fabric and then inserting the free end of such pin into the slot 17, 18. After this has been done, the locking member 20 is brought from the open position Fig. 2 to the closed or locking position, Fig. 85 3. It will be seen from this latter view that this movement brings the projection 23 close to the projection 19 and into a position in which the two projections together hold the pin 12 securely in the socket or slot portion 90 18 and prevent it positively from leaving the slot. It will also be seen from Fig. 3 that a certain effort has to be exerted to bring the projection 23 past the pin 12. After the projection 23 has passed the pin 95 12, it snaps in behind such pin, thus locking the plate 20 in its pin-retaining position. The outer ends of the projections 19 and 23 may even overlap slightly, as shown in Fig. 3. 100

During the closing movement of the locking plate 20, just described, the lip 24 not only serves to guide the plate 20 in the holder 13, but it also assumes a position across the open end of the slot 17, 18. If through 105 carelessness or for some other reason the securing pin 12 at the moment of closing of the locking plate 20, should not lie in the innermost portion of the slot 17, 18, in other words, if the pin 12, after the projections 110 19, 23 have been brought together, should happen to be in a position such as indicated

by the dot-and-dash circle in Fig. 3, the pin will still be held in the slot portion 17, the lip 24 preventing it from leaving such slot portion.

5 The projection 25 not only serves as a handle, as pointed out above, but it also acts as a lock for holding the plate 20 in its closed or locking position. This will be clear from Fig. 3 which shows that in order 10 to bring the plate 20 to its locking position illustrated, it is necessary to force the projection 25 over the upper edge 16' of the wall 16 of the holder 13. After the projection 25 has been snapped over this edge 16', 15 the plate or locking member 20 is securely held in its pin-locking position and there is no danger of its getting out of such position and releasing the pin 12.

Fig. 5 shows a construction differing from 20 the form of my invention illustrated by Figs. 1 to 4, only by the provision of two locking members 20' arranged side by side in a double holder or keeper consisting of two members 13', said locking members being 25 movable independently of each other. Each of the keepers 13' is of the same construction as the keeper 13, and each of the locking members 20' is of the same construction as the locking member 20. The 30 advantage of the duplication of the locking members as shown in Fig. 5, is that if one of these locking members should be brought accidentally to the open or pin-releasing position, there would still be the other locking 35 member to hold the pin 12 firmly in its position within the other member of the double keeper.

Preferably, in both forms of my invention, the locking members 20 or 20' are in 40 frictional contact with the adjacent inner faces of the keeper walls 14 and 15, and such frictional engagement will act as an additional safeguard to hold the locking members 20 or 20' and prevent their accidental 45 displacement.

Various modifications may be made without departing from the nature of my invention as set forth in the appended claims.

I claim as my invention:

- 50 1. A locking device for the pins of brooches and other articles, comprising a keeper having a slot with an opening for the passage of the pin, and a locking member pivotally secured to said keeper and having a portion adapted to be swung across said slot at a distance from said opening so as to hold the pin in the inner end of said slot, said portions being in frictional engagement with the walls of said keeper.
- 60 2. A locking device for the pins of brooches and other articles, comprising a keeper having a slot with an opening for the passage of the pin, and a locking member pivotally secured to said keeper and having a projection adapted to be swung across

said slot so as to hold the pin in said slot and means on said member cooperating with said pin for locking said member in its pin-holding position.

3. A locking device for the pins of 70 brooches and other articles, comprising a keeper having a slot with an opening for the passage of the pin, and a locking member secured to said keeper movably, said locking member having a portion adapted 75 to be moved across and to close off said slot adjacent to the inner end thereof and another portion adapted to close said slot adjacent to said opening.

4. A locking device for the pins of 80 brooches and other articles, comprising a keeper having a slot with an opening for the passage of the pin, the wall of said slot being formed with a projection located at a distance from the inner end of the slot, and 85 a locking member secured to said keeper movably and having a portion adapted to be moved toward said projection and to cooperate therewith to close off the inner portion of the slot from said opening. 90

5. A locking device for the pins of brooches and the like, comprising a keeper having side walls and an end wall connecting said side walls, said keeper also having a slot for the reception of the pin, and a 95 locking member pivoted to said side walls at a point opposite to said end wall and having a portion adapted to be swung toward said end wall and across said slot so as to close off the inner end of said slot from the 100 slot entrance, said portion being in frictional engagement with said side walls.

6. A locking device for the pins of 105 brooches and other articles, comprising a keeper having a pair of side walls provided with aligned slots, a locking member pivotally mounted between said side walls for movement to an opened or a closed position and also provided with a slot, each of said 110 slots having one end thereof open to permit the passage of the pin, and said side walls and member each being provided with a projection extending into its slot to provide a restricted passage connecting the inner closed end and the outer open end of 115 the slot, the projections of said member cooperating with the projections of said side walls to hold the pin within the inner closed end of the slot when said member is in its closed position and a portion of said member extending across the outer end of the side wall slots when said member is in said closed position.

7. A locking device for the pins of 125 brooches and other articles comprising a keeper having a pair of side walls and an end wall connecting said side walls, a locking member pivotally mounted between said side walls in frictional engagement therewith and movable to an opened or a closed 130

position, each of said side walls and said member being provided with a slot having one end thereof open, said side walls and member each having a projection extending into its slot to define a restricted passage-way connecting the inner closed end and the outer closed end of said slot, said projections when said member is in its closed position closing the inner end of said slot

to retain the pin therein, the projection on 10 said member engaging with said pin to lock said member in closed position and said member being further provided with a notch to engage said end wall to assist in locking it in closed position. 15

In testimony whereof I have signed this specification.

JOSEF PEJCHAR.
